UNITED STATES PATENT OFFICE

JAMES H. REICHART, OF MUNCIE, INDIANA

DESIGN FOR A SMOKING-STAND BODY

Application filed November 1, 1929. Serial No. 33,248. Term of patent 7 years.

To all whom it may concern:

Be it known that I, JAMES H. REICHART, a citizen of the United States, residing at the city of Muncie, in the county of Delaware and State of Indiana, have invented a new, original, and ornamental Design for a Smoking-Stand Body, of which the following is a specification, reference being had to the accompanying drawing, forming part thereof.

The figure is an elevational view of a smoking stand body, showing my new design.

I claim:

The ornamental design for a smoking stand body, as shown.

JAMES H. REICHART.
